UNITED STATES PATENT OFFICE

2,456,022

MANICURE APPARATUS

Noreen C. Rebo, Gorin, Mo.

Application March 18, 1947, Serial No. 735,521

2 Claims. (Cl. 132—73)

1

This application pertains to a new and useful manicuring set for use either by professional manicurists in beauty parlors and similar establishments, or by private persons at home.

A principal object of the invention is to provide such an apparatus, adapted to contain and support the instruments and supplies that are customarily used in the art of manicuring.

Another object of the invention is to provide a manicure apparatus that will carry a light for illuminating a desired portion of the manicure table, either from above or below or from both.

A further object is to provide a manicure apparatus that will contain means for heating desired pomades or lotions.

Other objects will appear to those skilled in the art.

The invention consists of various novel features of construction and operation, as hereinafter more fully described in connection with the accompanying drawings.

Figure 1 is a top plan view of the complete apparatus.

Figure 2 is a front view, partially in section, of the complete apparatus.

Figure 3 is a fragmentary vertical section through the central part of the device, taken along line 3—3 of Figure 2.

Figure 4 is a plan of one of the components.

Figure 5 is a plan of another component.

Figure 6 is a front view of still another component.

The device comprises a central base 10, circular in plan, as illustrated in Figure 1. Within the hollow base a circular wheel 11 is pivoted at its center on a vertical pivot 12, which pivot is eccentric with respect to the central base 10. The edge of the wheel 11 is serrated or knurled to provide traction. The size of the wheel 11 is such that a small segment of the edge projects beyond the rim of the central base 10, as is illustrated in Figure 1. The pivot 12 is supported by a lateral plate 13 extending across the hollow portion of the base 10. The hollow base 10 also comprises a circular top 16 and a circular bottom 17. The top 16 is apertured at one side, near the projecting edge of the wheel 11, and the aperture is filled or covered with a window 18 of clear glass or plastic. The lateral plate 13 is similarly apertured, and its opening may or may not be glazed. It will be observed that the top 16 and the plate 13 are fixed in position, and that the apertures in these members are always in alignment. The plate 13 is spaced from the top 16 sufficiently to afford room for the pivot 12, and the mounting of

2

the pivot is such as to permit ease of rotation of the wheel 11 on its pivot 12.

The wheel 11, shown more particularly in Figure 4, is formed with a plurality of openings 21 therein, a total of seven being illustrated. Of these, one opening may be round and the others finger nail-shaped, of varying sizes, for a purpose to be more fully described hereinafter. The holes 21 are concentrically arranged about the pivot 12, and so positioned that each can be brought into alignment with the glass window 18 in the top 16 by a manipulation of the edge of the wheel 11.

Directly underneath the window 18 and in alignment therewith is an electric bulb 25. The light from the bulb may be focused with the aid of a reflector 26 so that it will be directed through the window 18 at the proper time. The bulb 25 is mounted on the bottom 17, and access thereto may be effected by means of a circular door 27 that fits a similar opening in the bottom member 17. Two or more bayonets 28 serve to keep the door 27 in locked position in the bottom 17.

Secured at one side to the central base 10 is a circular stand 30, which is designed to support auxiliary apparatus and supplies. Within the stand 30 is a heating coil 31, to be used for heating cosmetic oils and other materials. On top of the stand 30, a removable pan 32 may be supported. This pan 32, shown more clearly in Figure 5, resembles a circular dish, having a central aperture adapted to hold a cup 33 for oil or similar material, and a plurality of peripheral cups of various sizes to hold cotton, pumice, paint, oil, polish, and other supplies used in the art, either directly in the cups or indirectly in bottles or jars.

A shallow tray 35 is adapted to rest within the rim of the pan 32 in such fashion as to result in a tight closure. The tray 35 itself is flanged and may be used to hold other supplies.

It will thus be apparent that the contents of the pan 32, or those of the removable cup 33, or those of the removable tray 35, may be warmed by the heating coil 31, selectively, singly or in combination, as the occasion may require. The presence and positioning of the containers, as well as the heating capacity of the coil 31, will give different warming effects to the contents.

Attached to the other side of the base 10 is another circular stand 40. This may or may not contain a heating coil 41. The stand is adapted to support a manicure bowl 42.

Two adjustable lights 45 and 46 will furnish additional illumination from above.

The apparatus operates as follows:

The finger nail of the patron is placed on the glass window 18, and the wheel 11 is revolved by the manicurist until an aperture 21 of the proper size is directly under the finger nail. The light from the bulb 35 will then illuminate the finger and enable the operator to carry out her duties with ease and efficiency.

The heating stand 30 will warm the materials so that they are of suitable consistency and of comfortable temperature. Similarly, the liquid in the manicure bowl 42 may also be warmed, if desired.

In consequence, this apparatus will serve as an efficiency cabinet, and enable the manicurist to render efficient service, with comfort to herself as well as to the patron.

What is claimed is:

1. A finger nail manicuring stand comprising a horizontal base to rest upon a support, said base comprising an upper plate and a lower plate, said plates being vertically spaced and formed near one edge with vertically registered openings, a light source on said base beneath said lower plate arranged for directing light upwardly through said registered openings, and a rotatable masking disk mounted on and beneath said lower plate, the edge of said masking disk projecting beyond an edge of said upper plate to facilitate rotation of said masking disk from a position above said upper plate, said masking disk being formed with a plurality of circumferentially spaced openings arranged to be selectively registered with said openings in the upper and lower plates by rotating said masking disk.

2. A finger nail manicuring stand comprising a horizontal base to rest upon a support, said base comprising an upper plate and a lower plate, said plates being vertically spaced and formed

near one edge with vertically registered openings, a light source on said base beneath said lower plate arranged for directing light upwardly through said registered openings, and a rotatable masking disk mounted on and beneath said lower plate, the edge of said masking disk projecting beyond an edge of said upper plate to facilitate rotation of said masking disk from a position above said upper plate, said masking disk being formed with a plurality of circumferentially spaced openings arranged to be selectively registered with said openings in the upper and lower plates by rotating said masking disk, a transparency covering the said opening in said upper plate, said registered openings being substantially wider than the width of a finger nail and some of said openings in said masking disk being substantially narrower than said registered openings.
